LOG FEED MECHANISM

Thomas W. Nicholson, Seattle, Wash.

Application February 1, 1954, Serial No. 407,362

9 Claims. (Cl. 144—249)

This invention pertains to mechanisms for feeding logs to processing machines and is particularly intended to feed logs to a machine for removing bark from them. By such mechanism logs are fed lengthwise and nonrotatively through such a machine.

Machines of various types have been devised for removing bark from logs, but the present log feeding mechanism has particular utility for use in conjunction with a log barking machine of the type which includes a rotary ring through which a log is fed for engagement by barking tools carried by such ring and moved orbitally around the log. Feed mechanism for use with such a machine must be capable of holding a log against appreciable lateral displacement, of preventing rotative movement of the log and of effecting uniform progressive lengthwise movement of the log through the barking machine, and it is a principal object of the present invention to provide mechanism having these attributes.

A further important object of the invention is to provide such mechanism which will be equally effective for feeding large logs and small logs and which can be adjusted readily for accommodating logs of different sizes.

Especially is it an object of such mechanism to be able to hold a log firmly against rotation about its axis by the use of apparatus of simple construction and which will afford minimum resistance to longitudinal movement of the log and hence will feed the log efficiently.

Great force is exerted on a log in removing the bark from it by the use of such a machine, and consequently such feed mechanism must be rugged to withstand the abuse to which it will be subjected during the barking of large and heavy logs. Also, it is important that such mechanism be designed to resist wear resulting from its use and for this reason it is desirable to have as little relative movement as possible between the surface of a log and the parts of the feed mechanism with which it comes into contact.

In accomplishing these objects the log feed mechanism incorporates positively moving log carrier means in the form of chains or live rolls, for example, in combination with upper adjustable hold-down devices such as a plurality of rotary ribbed heads which engage a log at circumferentially spaced locations. Both the carrier or transport means and the rotary hold-down heads grip the log in a manner to resist its rotative movement while producing little or no appreciable resistance to lengthwise movement of the log. A more effective feed is obtained by gripping the log at opposite sides of the barking mechanism so that the log is both pushed and pulled through the barking machine while held firmly in the manner described at both sides of the barking mechanism.

Additional objects and advantages of the log feed mechanism will be discussed in the following specific description of representative types of such mechanism shown in the drawings.

Figure 1 is a plan view of a preferred type of log feeding mechanism incorporating a chain type carrier, and

2

Figure 2 is a vertical sectional view through such mechanism taken on line 2—2 of Figure 1.

Figure 3 is a fragmentary top perspective view of a portion of such mechanism.

5 Figure 4 is a plan view of a different type of such mechanism incorporating a chain-driven flight type of carrier and utilizing different hold-down devices.

Figure 5 is an enlarged transverse sectional view through the mechanism taken on lines 5—5 of Figures 4 and 6. Figure 6 is a fragmentary longitudinal vertical section through the carrier along lines 6—6 of Figure 5.

10 Figure 7 is a plan view and Figure 8 is a side elevational view of still a further type of log feeding mechanism incorporating a live roll carrier and hold-down devices like those in the form of Figure 4. Figure 9 is an elevation view of the apparatus showing the hold-down device taken on line 9—9 of Figure 7, and Figure 10 is a top perspective view of the hold-down device illustrating the manner in which it engages a log. Figure 11 is a side elevation view of one type of live roll used in the carrier of such mechanism with parts broken away, and Figure 12 is a transverse sectional view through such a roll on line 12—12 of Figure 11. Figure 13 is a side view of a different form of live roll which may be used in the carrier of such mechanism, and Figure 14 is a transverse section through such roll along line 14—14 of Figure 13.

15 Figure 15 is a transverse section showing another form of device; Figure 16 is an enlarged section on line 16—16 of Figure 15.

20 As has been stated, the log feeding mechanism of the present invention finds its greatest utility in feeding logs lengthwise and nonrotatively through a log barking machine of the rotary ring type. Such a barker is illustrated representatively in Figures 1, 2, 4, 7 and 8 as incorporating a rotary ring 1 which is mounted rotatively in a supporting ring 10. This latter ring is mounted in a frame 11 which is guided for vertical movement in ways 12 as shown in Figure 2. This frame can be adjusted vertically by operation of a fluid cylinder 13 moving the frame supporting rods 14 vertically to dispose the center of the rings 1 and 10 coaxial with a log carried by the log feeding mechanism. The barking ring 1 is rotated to perform the barking operation by the chain 15 which 25 is driven by the electric motor 16. The ways 12, cylinder 13 and motor 16 are all supported on suitable framework 17.

25 Figures 1, 2 and 3 show the preferred type of hold-down mechanism. In this instance the log L shown in Figure 2 rests directly on and is cradled between two chains 2 extending in spaced parallel relationship axially of the barking machine ring, and hence lengthwise of the direction in which the log is to be moved through such ring. Preferably these chains are spaced apart a 30 distance approximately equal to the radius of a log of medium size from which the bark will be removed by the barking machine. When carrying even the smallest log to be fed through the barking machine, therefore, the lowest portion of the log will not extend much below the chains, so that the weight of the log will not exert a great force tending to wedge the chains apart. At the same time, the spacing between the chains will be sufficient so that when the largest log to be processed is resting on them such log will be engaged at locations 35 spaced apart enough to afford adequately stable support to the log to avoid any appreciable chance of the log rolling off the chains when held down properly.

35 The entire weight of the log will rest on the chains 2 of the log carrier section on the feed side of the barking machine as the log is being moved into it, and the log will be supported jointly by such chains and by the chains 2' of the carrier section at the discharge side of the log.

barking machine as the log progresses through it. Since the log is thus carried bodily by the chains engaging the log over a great longitudinal extent, the frictional engagement between the log and chains produces a great resistance to movement of such chains relative to the log. Consequently, there is little danger of the chains slipping along the log instead of moving the log positively in synchronism with the chains, because such slippage could occur only if the log were subjected to a very great force opposing its lengthwise movement. This chain type of log carrier therefore feeds the log through the barking machine very reliably at a predetermined constant rate of speed.

The chains 2 and 2' are supported in parallel channels on plates beneath them and extend between spickets carried by cross shafts as shown in Figs. 1, 2 and 3. Each cross shaft carries two sprockets, one for each chain, and the two sprockets on each shaft are interconnected and definitely spaced by a heavy hollow axle through which the cross shaft extends. The corresponding sprockets at one end of chains 2 are rotated positively by the shaft carrying them, which is turned by chain 22 driven by the motor 23, as shown in Figure 1. Chains 2 will extend axially of the barking ring for a substantial distance and preferably over nearly the full length of a log of average length from which the bark is to be removed by the barking machine. Chains of such length will insure that they exert a firm, reliable feeding grip on a log to be barked. The chains 2' at the discharge side of the barking machine need not be as long as the chains at the feed side of the machine, and they are supported and driven generally in the same manner.

Beyond the discharge ends of chains 2' live rolls 24 may be provided to carry the barked log away from the barking machine. These rolls may be driven by interconnecting chains 25 and a chain 26 may connect the shaft of roll 24 closest to chains 2' and the adjacent sprocket shaft 27 of such chains. By such interconnection the chains 2' and rolls 24 will all be driven at the same speed and at a speed synchronized with the speed of the feed chains 2. Suitable supporting structure will, of course, be provided for the chain sprocket shafts and the roll shafts, as indicated in the drawings.

The chains 2 and 2' will deter movement of the log in a generally horizontal direction transversely of the chains, but the weight of the log may not be sufficient to insure that it will be held down in firm engagement with the chains under stresses exerted on it by the barking operation. Consequently, a plurality of rotary hold-down devices are arranged above the chains 2 and 2' to engage the upper portion of a log. Preferably these rotary hold-down devices 3 are rotary heads arranged in pairs, one at each side of a vertical plane extending lengthwise and centrally of the log carrier. The rotary heads of each pair should be spaced apart a substantial distance so that they will engage spaced locations on the upper surface of the log.

Each rotary head 3 is journaled on the end of an arm, which may be a lever arm 30 swingable about a supporting pivot 31. In the rotary hold-down head arrangement shown in Figures 1, 2 and 3, swinging of the lever 30 is effected by a fluid piston and cylinder device 32, one end of which is connected by pivot 33 to the arm 30 at a location between the hold-down head 3 and the arm pivot 31. The other end of the piston and cylinder device is connected by a pivot 34 to a stationary reaction bracket on the framework 35, which supports the hold-down mechanism. Contraction of the fluid piston and cylinder device will therefore swing the arm downward about pivot 31 to press the hold-down head firmly against a log while extension movement of such device will swing the hold-down head away from the log to enable a new log which may be of larger diameter to be moved beneath the hold-down head.

Any number of pairs of such lever-mounted rotary hold-down heads may, of course, be provided, but it has been found that two pairs of such heads adjacent to the infeed side of the barking machine and two pairs of such heads adjacent to the discharge side of the barking machine, as shown in Figure 1, are adequate to hold a log firmly in contact with the chains 2 and 2'. For usual control the piston and cylinder devices 32 for the two levers of each pair of such hold-down heads may be connected together, but each individual device should also be operable separately to enable a log to be shifted laterally by pressure of one device. Both hold-down heads of any pair can thus be moved upward or downward simultaneously and independently of such movement of any other pair of heads, or any one hold-down device can be moved separately at will. Also because fluid-actuated devices are employed, such as air cylinders, each hold-down head may exert substantially the same force on a log irrespective of the swung position of the hold-down head supporting arm 30 within rather wide limits.

By the use of rotary hold-down devices adequate pressure may be exerted on a log without creating appreciable resistance to movement of the log lengthwise effected by the log carrier such as chains 2 and 2'. It is important, however, when such feed mechanism is used to feed logs to a rotary ring barker, for the feed mechanism to restrain rotation of the log. Both the log carrier and the hold-down devices contribute to this action. The chains engage the log on longitudinal elements and themselves produce considerable resistance to rotation of the log when it is pressed against them by the hold-down devices. The hold-down devices also are formed to grip the log firmly for preventing its rotation. A friction wheel surface, such as a rubber tire, can be used.

Particularly in Figures 2 and 3 a rotary hold-down device head 3 is shown as incorporating several spaced annular ribs cooperatively conforming generally to the arcuate contour of the log's periphery. In this particular instance the rotary head of such hold-down device may be a single wheel having a grooved periphery forming these ribs or such ribs may be formed by the peripheries of parallel, coaxial disks 36 of different diameters which are independently journaled on the shaft carried by arm 30. Such rotary hold-down head disks are sufficiently thick so that they will not yield appreciably under lateral pressure exerted on them by tendency of the log to rotate, yet they will be thin enough to engage the log surface with concentrated pressure. The ribs spaced axially of the rotary head improve the contact between such head and the log to resist rotational movement thereof and displacement of the log transversely of its length. Such log movement resisting contact is improved for logs of different size by shaping the ribbed rotary heads tapered away from their supporting arms 30 as shown in Figures 2 and 3. To maintain the gripping effectiveness of the disks 36 cleaning fingers 37 are supported by a bar 38 in positions inserted between the disks so that, as they are rotated by contact with a log, bark debris will be removed from the spaces between the disks.

In operation of the feed mechanism shown in Figures 1, 2 and 3 a log will be carried to the chains 2 and movement of these chains will draw the log progressively farther onto them. Before the end of the log reaches the first pair of hold-down devices, the fluid actuators 32 will be extended to raise the rotary hold-down heads 3 of such pair and perhaps of the other pairs if the log ahead has cleared the barking ring. As the end of the log passes beyond each pair of hold-down devices, the heads of each pair in turn will be lowered into engagement with the log and pressure will be maintained in the cylinders of the fluid actuators to exert continuous positive hold-down pressure on the log until its trailing end has moved beyond the barking ring.

The operation of the log feed mechanism shown in

Figures 4, 5 and 6 is similar to that described above. In this instance, however, instead of the log resting directly on carrier chains, the chains 4 do not support any of the weight of the log. Instead, such claims merely constitute interconnecting members to space and drive log supporting generally planar, plate-shaped flights 40. The upper edges of these flights are of generally V shape and have projections or teeth arranged at intervals along the length of such upper edge to effect a secure grip on the log. The chains are connected to projections 41, 10, respectively, extending downward adjacent to opposite ends of the flight. Lengthwise movement of the chains 4 will, of course, be coordinated, and by connecting such chains in spaced relationship to the flights 40 such flights will be held in positions with their planes perpendicular to the chains as they travel around the sprockets at the opposite ends of the chain loop.

The supporting mechanism for the flights 40 includes posts 42 which support I-beam rails 43 extending parallel to the direction of movement of the chains. Wear strips or tracks 44 are mounted along the upper flanges of the rails 43 on which the overhanging opposite ends of the flight 40 rest, respectively. Each end of each flight is provided with a shoe 45 of considerable extent transversely of the flight plane to provide a sliding surface of sufficient extent in the direction of flight movement to prevent tilting of the flight under the influence of the force couple resulting from the pull of the chains 4 below the frictional resistance occasioned by contact of the shoes with the wear strips 44.

In this form of log feed mechanism the hold-down devices are somewhat different from those previously described, and these are shown best in Figures 4, 9 and 10. In this instance the lever arms 5 are mounted on pivots 50 located generally centrally between their ends. The adjacent ends of each pair of lever arms carry rotary hold-down heads 51 rotatable on axles extending lengthwise generally in continuation of the lever portions carrying such rotary heads. The lever portions at the other sides of the pivots respectively are disposed at an angle to the rotary head carrying portions of the lever arms, so that such rotary head carrying portions are generally upright while the portions of the lever arms to which the control force is applied extend generally horizontally.

To the swinging ends of the generally horizontal lever portions are pivotally connected piston and cylinder fluid actuators 52, which are supported from the mounting structure 53 by pivots 54. When the actuators are contracted, therefore, the rotary head carrying lever portions will be swung away from each other to retract the hold-down heads 51. Conversely, extension of the actuators will swing the levers to move the hold-down heads inward into contact with a log L. In Figure 10 the hold-down levers are illustrated in retracted positions in full lines and in holding positions in broken lines. When in such holding position, fluid under pressure will be impressed upon the fluid-actuated devices so that the force of the rotary hold-down heads will be maintained against the log.

By journaling such rotary heads on axles extending generally in prolongation of the lever portions, the axis of rotation of each hold-down head will extend generally parallel to a tangent to the log at the location of hold-down head contact with it, as illustrated in Figure 9, and the rotary heads of each pair of hold-down devices will engage the log at spaced locations. While, as previously discussed, the rotary hold-down heads may be composed of a plurality of independently journaled disks, a reasonably satisfactory grip of the peripheries of the hold-down heads on the log opposing its rotation about its longitudinal axis may be afforded by spaced annular ribs 55 formed by grooving the peripheries of the rotary heads 51. Preferably these ribs taper to a reasonably sharp edge and the intervening groove may be V-shaped in cross section, as shown best in Figure 9.

The log barking machine with which the feed mechanism shown in Figures 4, 5 and 6 may be used, as illustrated in Figures 4 and 9, is the same as that described in connection with the log feed mechanism of Figures 1, 2 and 3, and consequently, no further description of such mechanisms at this point is necessary. The ring 1 carrying the barking tools may be adjusted by actuation of the cylinder 13 to center the ring with logs of various size, and the sequence of feeding the log, engaging it successively with the hold-down devices and releasing the hold-down devices from the log will be the same as described already.

In Figures 7 and 8 log feed mechanism is illustrated which utilizes the same type of hold-down devices described in conjunction with Figures 4, 9 and 10, and again may be used with a rotary ring barking machine, as already described. This feed mechanism, however, differs in the log carrying apparatus. Here the log carrier includes a set of infeed rolls and a set of discharge rolls, which are shown somewhat diagrammatically in Figures 7 and 8. The infeed rolls set may include a series of idler rolls 6 at locations remote from the barking machine, and a series of powered rolls 60 close to the barking machine. Such powered rolls may be interconnected by drive chains 61 which are driven by the motor 62 through chains 63. Any convenient number of idler and powered rolls may be used.

Similarly, on the discharge side of the barking machine a series of powered rolls 64 is located adjacent to the barking machine, which are interconnected by chains 65 and driven by motor 66 through chain 67. Beyond the rolls 64 in the direction of log movement are idler rolls 68 on which the log will be supported when discharged from the live rolls 64. From these idler rolls a log may be lifted by swinging arms 7, which are carried by a shaft 70 oscillatable by a fluid cylinder actuator 71. By swinging the arms upward logs may be pushed from the rolls 68 whereupon they will roll down the arms 7 onto ways 72 for further processing.

The shape of typical rolls which may be used as the live rolls can vary, but representative shapes are illustrated in Figures 11 to 14. Again, in order to prevent the log from being turned about its longitudinal axis, the log carrier and the hold-downs should cooperate to grip the periphery of the log firmly. Preferably a live roll is located under the rotary heads of each hold-down device, and such rolls may have the configuration shown in Figures 11 and 12, being made of two frusto-conical sections 8. Each section has on its periphery annular ridges 80 which have notches 81 at intervals to increase the tractive effort longitudinally of the log. The sharpened annular ridges, like the ridges 55 of the hold-down wheels 51, will dig into the log periphery to resist rotation of the log. The two conical roll segments are mounted with their smaller ends in abutment on a shaft 82.

Carrier rolls which are not located directly under hold-down heads would not be particularly effective in resisting rotation of a log. It is desirable, however, that they produce maximum tractive force to feed the log endwise. For such rolls, therefore, the configuration shown in Figures 13 and 14 may be employed. Again, these rolls preferably are composed of two frusto-conical sections 83 mounted with their smaller ends in abutment on a shaft 84. Traction ribs 85 are formed on each of these sections extending longitudinally of them. The idler rolls, of course, merely support the log, and consequently need not have any ribs.

Since the hold-down devices and their operation have been discussed previously, it will be evident how they are manipulated during feeding of a log by the roll type carrier described, so that no further description of this embodiment of the log feed apparatus is necessary.

In Figures 15 and 16 an alternative type of supporting structure for rotary hold-down heads is illustrated, which,

of course, may be utilized with any of the log carrier arrangements discussed above. In this instance the rotary hold-down heads 3 are shown as incorporating several annular ribs tapered in the group away from the supporting arms 9, like those of Figures 1, 2 and 3. These rotary heads are journaled on axles extending substantially parallel to tangents to the log at the locations of rotary head contact with the logs as in the hold-down devices previously described. This hold-down mechanism differs, however, in the manner in which the axles are supported. Only one pair of hold-down devices is illustrated in Figure 15 but it will be understood that any number of pairs may be utilized, arranged lengthwise of the log carrier comparable to the arrangement of hold-down devices shown in Figures 1, 4 and 7, for example.

The log carrier with which the hold-down devices operate incorporates flights 40' generally comparable to the flights 40 of the log carrier mechanism shown in Figures 4, 5 and 6, but having a single central projection 41' located centrally of the flight's lower edge to which a single drive chain 4' is secured. Shoes 45' on the lower corners of the flights 40' ride on supporting tracks such as the angle members 44'. The chain 4' will, of course, be of the endless type and will be attached to log supporting flights 40' at intervals suitable to enable such flights to support a log properly in a position centrally between the hold-down supports.

The rotary hold-down heads 3 are mounted on axles carried by arms 9, which arms are mounted on wheeled carriages 90. Such carriages may be of generally rectangular shape and have a wheel journaled at each corner to rotate about an axis transversely of the rotative axes of hold-down heads 3 and extending generally parallel to a log L on the log carrier. As shown in Figure 16, the wheels on opposite sides of the carriages 90 are received in arcuate channel tracks 91. In Figure 15 the tracks on the near side of the view have been broken away to reveal the carriage structure. These tracks are supported by suitable posts 92 supported on beams 93.

The curvature of the tracks 91 and their angularity relative to beams 93 will be such that tracks on the opposite sides of the log carrier converge downward. As the carriages 90 are moved upward along such tracks, therefore, the spacing of the rotary hold-down heads 3 will increase at a rate progressively greater for equal incremental movements of the carriages. The spacing of the tracks at opposite sides of the log carrier adjacent to their lower ends will be sufficiently great to accommodate between the tracks a log of the maximum size desired to be processed by the log barking machine. A medium sized log is illustrated as being engaged by the hold-down heads in Figure 15 and broken lines indicate a smaller log and a log of substantially the maximum size which could be handled by the mechanism. The positions which the hold-down devices would occupy along rails 91 for engaging the largest log indicated are illustrated in broken lines.

Movement of the carriages 90 along the tracks 91 is effected by fluid piston and cylinder actuators 94 which are pivotally connected to projections 95 extending from the carriage opposite the extension of head supporting arms 9. The opposite ends of such actuators are pivotally supported by pivots 96 carried by suitable stationary reaction structure mounted on beams 93. As in the previous types of hold-down devices discussed, these actuators may be controlled jointly to move the hold-down heads upward or downward simultaneously along tracks 91.

The log feed mechanism incorporating the hold-down devices shown in Figures 15 and 16 can be operated in a manner similar to the other forms of apparatus discussed above.

I claim as my invention:

1. Log feed mechanism comprising carrier means

operable to support and to advance a log longitudinally and including gripping means operable when the log is pressed thereagainst to resist rotation of the log about its axis, and anti-rotation hold-down means including two lever arms disposed one at each side of said carrier means, a pivot supporting one end of each of said lever arms remote from said carrier means for swinging about an axis parallel to such direction of log advance, a plurality of independent log engaging disks mounted on the swinging other end of each of said lever arms, having smooth peripheries, means supporting said disks and constraining rotation thereof to concentric rotation about a common axis extending transversely of the direction of movement of said carrier means, and means connected to each of said lever arms between its pivot and its disks and operable to exert a force on said lever arms in a direction to move said disks toward said carrier means and press the edges of said disks against upper portions of a log on said carrier means which are spaced transversely of the log to deter rotation of the log and to press the log downward against said carrier means.

2. Mechanism comprising carrier means operable to support and to advance a log longitudinally and including chain transport means advancing with the log and operable when a log is pressed thereagainst to resist rotation of a log about its axis, and anti-rotation hold-down means including two lever arms disposed one at each side of said carrier means, a pivot supporting one end of each of said lever arms remote from said carrier means, a head including several rotative axially spaced annular log-engaging ribs mounted on the swinging other end of each of said lever arms and rotative about an axis extending transversely of the direction of movement of said carrier means, and fluid pressure operated means connected to each of said lever arms between its pivot and its head and operable to exert a force on said lever arms in a direction to move said heads toward said carrier means and press said ribs against upper portions of a log on said carrier means which are spaced transversely of the log to deter rotation of the log and to press the log downward against said carrier means.

3. Log feed mechanism comprising carrier means operable to support and to advance a log longitudinally, and anti-rotation hold-down means including two lever arms disposed one at each side of said carrier means directly opposite transversely of the direction of movement of such means, two pivot means disposed substantially level with said carrier means at opposite sides of said carrier means, each pivot means defining an axis extending substantially parallel to the direction of log advance effected by said carrier means and supporting one of said lever arms inclined upwardly toward said carrier means for swinging relative thereto, a rotary head incorporating several rotative axially-spaced annular log-engaging ribs carried by the swinging end of each of said lever arms and rotative about the same axis extending transversely of the direction of advance of the log, and means operable to swing said lever arms to move said heads toward said carrier means into positions engaging the upper portion of a log on said carrier means which are spaced transversely of the log and located at opposite sides of the vertical diametral plane of the log for restraining rotation of the log.

4. Log feed mechanism comprising carrier means operable to support and to advance a log longitudinally and including chain transport means advancing with the log and operable when a log is pressed thereagainst to resist rotation of such a log about its axis, and anti-rotation hold-down means including two arms disposed one at each side of said carrier means, a head including several rotative axially spaced annular log-engaging ribs mounted on each of said arms and rotative about the same axis extending transversely of the direction of movement of said carrier means, means supporting said arms for movement to move said heads toward and away from said

carrier means, and means connected to each of said arms and exerting a force thereon in a direction to move said heads toward said carrier means and press said ribs against upper portions of a log on said carrier means which are spaced transversely of the log to deter rotation of the log and to press the log downward against said carrier means.

5. Log feed mechanism comprising carrier means operable to support and to advance a log longitudinally and operable when a log is pressed thereagainst to resist rotation of a log about its axis, and anti-rotation hold-down means including two heads spaced transversely of the log and located at opposite sides of the vertical diametral plane of the log, each head including several rotative axially spaced annular log-engaging ribs rotative about the same axis extending transversely of the direction of movement of said carrier means, means supporting said heads for movement toward and away from said carrier means, and means connected to said supporting means and exerting a force thereon in a direction to move said heads toward said carrier means and press said ribs against upper portions of a log on said carrier means which are spaced transversely of the log to deter rotation of the log and to press the log downward against said carrier means.

6. The log feed mechanism defined in claim 5, in which the means supporting the heads for movement toward and away from the carrier means includes two tracks disposed one at each side of the carrier means in generally upright position but convergent downwardly, and carriages guided for movement along said tracks, respectively, on which the heads are mounted, and the means connected to the supporting means and exerting a force thereon in a direction to move the heads toward the carrier means includes means operable to move said carriages toward the carrier means.

7. The log feed mechanism defined in claim 5, in which the carrier means includes log-supporting gripping plate flight means disposed in an upright plane and having log-gripping projections on its upper edge operable when a log is pressed thereagainst to resist rotation of the log about its axis.

8. The log feed mechanism defined in claim 5, in which the carrier means includes endless chain means, a plurality of log-supporting members spaced lengthwise of said chain means and secured thereto at intervals, respectively, for movement thereby, and two rails parallel to each other

and to the length of said chain means, spaced farther apart than the width of said chain means and disposed with said chain means therebetween, said rails being engageable by said log-supporting members to support the log-supporting members by said rails.

9. The log feed mechanism defined in claim 5, in which the carrier means includes a chain movable lengthwise of the direction of log advance, a plurality of spaced log-supporting gripping flights secured to said chain at intervals, respectively, and operable to support a log thereon and to resist rotation of the log about its axis when pressed thereagainst, and spaced rails disposed transversely of said flights and engageable by said flights to support the same, said flights having means projecting downwardly therefrom and engaging said rails to limit shifting of said flights transversely of said rails.
